CLAIM

The ornamental design of a caliper body of a disc brake for vehicles, as shown and described.

DESCRIPTION

FIG. 1 is a front perspective view of a caliper body of a disc brake for vehicles;

FIG. 2 is a rear perspective view of FIG. 1;

FIG. 3 is a top view of FIG. 1;

FIG. 4 is a bottom view of FIG. 1;

FIG. 5 is a front view of FIG. 1;

FIG. 6 is a rear side view of FIG. 1;

FIG. 7 is a left side view of FIG. 1; and,

FIG. 8 is a right side view of FIG. 1.

The broken lines immediately adjacent surfaces depicted in solid lines represent boundaries of the claim.
